Patented Feb. 6, 1917.

UNITED STATES PATENT OFFICE.

JOHN A. HURST, OF NEW PHILADELPHIA, OHIO.

COLLAPSIBLE EGG-CASE.

1,215,278.

Specification of Letters Patent. Patented Feb. 6, 1917.

Application filed March 1, 1916. Serial No. 81,502.

To all whom it may concern:

Be it known that I, JOHN A. HURST, a citizen of the United States, residing at New Philadelphia, in the county of Tuscarawas and State of Ohio, have invented new and useful Improvements in Collapsible Egg-Cases, of which the following is a specification.

This invention relates to shipping cases and it consists in the novel features herein-after described and claimed.

An object of the invention is to provide a case especially adapted to be used for the purpose of transporting eggs and with this object in view the case comprises a pan shaped bottom member having side panels and end panels hingedly connected therewith. Top panels are hingedly connected with the side panels and when the crate is in setup position or condition the said top panels rest at their ends upon ledges provided at the inner side of the end panels. Suitable securing devices are provided for connecting the corner portions of the end panels with the corner portions of the side panels and a partition is adapted to be used in the case, the said partition being provided at its opposite edges with flanges adapted to interlock with flanges provided at the inner surfaces of the side panels.

In the accompanying drawing:—

Figure 1 is a perspective view of the case showing the parts thereof collapsed.

Fig. 2 is a similar view showing the parts in setup position.

Fig. 3 is a top plan view of the case showing the parts thereof spread out.

Fig. 4 is a detailed sectional view showing one of the top panels locked in engagement with one of the end panels.

Fig. 5 is a similar view showing one of the end panels locked in engagement with one of the side panels.

Fig. 6 is a similar view showing the partition panel locked in engagement with one of the side panels.

The case comprises a pan shaped bottom member 1 having side panels 2 and end panels 3 hingedly connected therewith. The side panels 2 are provided at their ends with inturned flanges 4 having at their upper ends recesses 5. The end panels 3 are provided at their opposite edges with inturned flanges 6 and the said end panels are provided at their upper corner portions with recesses 7 adapted to register with the re-

cesses 5 when the said panels are in setup position. Hooks 8 are pivotally mounted at the outer surfaces of the end portions 3 and their bill ends are adapted to be swung down into the registering recesses 7 and 5 whereby the side and end panels are held in setup position with relation to each other. The end panels 3 are provided at their inner surfaces and in the vicinity of their free edges with inwardly disposed ledges 9 and the said end panels are provided at their outer surfaces with suitable handles 10. Top panels 11 are hingedly connected with the free edges of the side panels 2 and when the parts of the case are in setup position the top panels are adapted to rest at their ends upon the ledges 9 and the inner edges of the said panels 11 approximately meet each other. The side panels 2 are provided at their inner surfaces and at points midway between their ends with hook shaped flanges 13 and a partition wall 14 is adapted to be positioned in the case between the ends thereof, the said wall being provided at its edges with returned bends 15 which may slidably engage in the flanges 13 whereby the immediate portions of the side panels 2 are restrained against spreading with relation to each other when the parts are in setup position.

Assuming that the parts of the case are in setup position suitable fillers of pasteboard or other material may be arranged in the case at the opposite sides of the partition wall 14 and the openings or spaces in the said fillers may be used for holding eggs during transportation. When the filled case reaches its destination and is emptied of its contents it may be collapsed or folded in the following manner. The top panels 11 are swung in upward and outward directions and then the hooks 8 are swung up out of engagement with the registering recesses 7 and 5. The end panels 3 are then folded back and the top panels 11 are folded back against the outer surfaces of the side panels 2. The said side panels 2 are then folded down in over the bottom member 1 and the end panels 3 are then folded down over the side and top panels and the flanges 6 of the said end panels may extend along the side walls of the pan shaped bottom member 1. Therefore, it will be seen that when the parts are in collapsed position they are approximately received within the pan shaped member 1 and the said parts may be

5 tied by using cord or wire and the handles 10 may be used for holding the collapsed case. Prior to folding the side panels down into the pan shaped bottom member the partition wall 14 may be laid upon the said bottom member and consequently it is secured and retained when the side and end panels are folded down toward the bottom member.

10 From the foregoing description taken in conjunction with the accompanying drawing it will be seen that a shipping case of simple and durable structure is provided and that the parts may be folded in compact relation for shipment or storage and consequently the case may be conveniently and 15 economically handled and shipped in transportation both in delivering goods and in its return to a producer.

20 Having described the invention what is claimed is:

A shipping case comprising a bottom member, side and end panels hingedly connected therewith, top panels hingedly connected

25 with the side panels, the end panels having ledges upon which the ends of the top panels may rest when the parts are in setup position, the said side panels having at their ends angularly disposed flanges provided at their ends with recesses which are located beyond the inner surfaces of the side panels, the said end panels having at their free edges and at points within their side edges recesses adapted to register with the recesses in the flanges of the side panels and hooks pivoted to the end panels at the opposite sides of the median lines thereof and engageable in said recesses when the same are in register with each other to hold the side and end panels against movement with relation to each other.

30 In testimony whereof I affix my signature in presence of two witnesses.

JOHN A. HURST.
